UNITED STATES PATENT OFFICE.

JOSEPH F. JOY, OF NORTH BELLE VERNON, PENNSYLVANIA.

GATHERING MECHANISM FOR COAL-LOADING MACHINES.

1,295,173.

Specification of Letters Patent. Patented Feb. 25, 1919.

Application filed May 9, 1918. Serial No. 233,477.

To all whom it may concern:

Be it known that I, JOSEPH F. JOY, a citizen of the United States of America, residing at North Belle Vernon, in the county of Westmoreland and State of Pennsylvania, have invented certain new and useful Improvements in Gathering Mechanism for Coal-Loading Machines, of which the following is a specification.

10 The present invention relates to certain new and useful improvements in gathering mechanisms for coal loading machines and more particularly for that class of loading machines which are adapted to gather coal

15 from the floor of a mine and transfer it to conveniently placed cars for transportation from the mine, an example of which is shown and described in my pending application, Serial #132,175, filed Nov. 18, 1916.

20 In the mining of coal, it is customary to undermine the face of the working place and then blast the coal from its solid state by the use of explosives. When this is done, some of the coal is broken away and left in heaps

25 adjacent the working face, from which it must be loaded into cars, entailing labor of the most arduous character. However, a greater quantity of coal is shattered, but remains standing in a semi-solid state.

30 It is the especial object, therefore, of the present invention, to provide a gathering mechanism of the class described in which the gathering means *per se* may not only move the material onto a conveyer, but also

35 break down, in lumps of desirable sizes, this coal left standing.

A further object is to provide a gathering member which may yield vertically when a lump of coal of unusual size becomes wedged

40 between the gathering member and the shoe which is attached to the forward end of the conveyer which transfers the coal to the cars.

45 A still further object is to provide means whereby the gathering member may be raised manually to direct the same into crevices in the face of the vein at different distances from the mine floor and to lift the gathering member off of the mine floor when the machine provided with this gathering

50 mechanism is moved from one room to another.

With these general objects in view and others that will appear as the nature of the invention is more fully understood, the same

65 consists in the novel construction, form and

arrangement of parts hereinafter more fully described and shown in the accompanying drawings, in which—

Figure 1 is a side elevation of the gathering mechanism secured in place upon a conveyer, only a fragment of the conveyer being shown, partly in section.

Fig. 2 is a plan view of the device shown in Fig. 1.

Fig. 3 is an enlarged sectional detail view of the means employed to raise the gathering member, taken approximately on line III—III of Fig. 1.

Like numerals refer to similar parts in the several figures and referring more in detail to the drawings, 5 indicates the conveyer which is of the well known chain and scraper type and consists broadly in guideways 6 in which move the spaced chains 7 which are connected together by the scraper cross bars 75

8. A shoe 9 is attached to the forward end of the conveyer 5 and has an upwardly extending lip 10 overlying the transverse driven foot shaft 11 of the conveyer 5.

An inverted U-shaped frame or supporting member 12 has its opposite leg portions 13 riveted or otherwise rigidly secured to the side plates 14 of the conveyer 5, and a shaft 15 is journaled through said leg portions. Upon one end of the shaft 15 is a beveled gear 16 which meshes with the beveled gear 17 secured on the shaft 18 which may be driven in any suitable manner, such as by gearing to the head shaft of the conveyer 5, not shown. A bearing bracket 19 supports the shaft 18 and retains the gears 16 and 17 in mesh with each other. A beveled gear 20 is secured on the shaft 15 approximately midway between the ends thereof, and a beveled gear 21 secured on the forwardly extending shaft 22 is retained in mesh with the gear 20 by the bearing bracket or shaft hanger 23 through which said shaft 22 is journaled.

Upon the forward end of the shaft 22 is carried a spiral auger conveyer and breaking down member which greatly increases in size from its forward pointed end to the rear end thereof.

A forwardly extending spring member 25 is secured to the U-shaped member 12 and extends downwardly to a point where the shaft 22 is journaled therethrough as at 26. This member 25 constitutes a hanger for the shaft 22 and is formed of spring metal to 110

allow shaft 22 and the gathering and breaking down member or auger 24 to yield vertically upwardly, it being noted that the bearing bracket 23 is provided with bearings 27 loosely surrounding the shaft 18 thus allowing this vertical movement of the shaft 22 and auger 24.

Extending forwardly from and midway between the leg of the U-shaped member 12 is a bracket 28 in the arms 29 of which is journaled the shaft 30 to which is secured the drum 31 which is adapted to be rotated manually by operation of the handle 32. A cable 33 is secured to the drum 31 and wound therearound, the other end of the cable being secured in the eye 34 of a swiveled collar 35 loosely seated within a groove in the member 36 which is secured to the shaft 22. A ratchet 37 is secured to the shaft 30 adjacent the handle 32 and such ratchet is engaged by pawl 38 which is pivotally mounted upon one of the arms 29, to thus prevent backward rotation of the drum at all times except when said pawl is manually disengaged from the ratchet.

When a loading machine provided with the present gathering mechanism has been brought into the room where coal is to be loaded, the gathering member 24 is lowered, partially by its own weight, and partially by the action of spring 25, into contact with the floor of the mine when the pawl 38 is released from the ratchet 37, and the machine is advanced into close proximity to the face of the vein. An undercut is first made in the face of the vein, and then the pointed end of the auger 24 is moved into the space formed by this undercut or into crevices in the coal after the same has been blasted. Rotation is imparted by suitable means to the shaft 18 and such rotation is transmitted to the auger 24 through gears 16, 17, 20 and 21. The fin of the auger or gathering member 24 engages with the coal and by reason of the fact that the fin extends in a spiral direction, the same screws into the face of the vein and also pulls quantities of coal away from the face of the vein and carries the same onto the conveyer 5. When the auger has broken away coal for a sufficient height, the machine is advanced and the auger moved farther into the undercut and the larger end of the gathering member will engage with the underface of the coal and continue this breaking down and loading operation.

In case a large lump of coal becomes wedged between the fin of the gathering member 24 and the shoe 9, the spring member 25 will allow the gathering member to yield upwardly, thus preventing the breakage of the fin. When the machine is to be moved along the floor of the mine, the handle 32 is rotated in the direction of the arrow

in Fig. 1 to wind the cable 33 upon the drum 31 and raise the shaft 22 and the gathering member 24.

This operation may be repeated until the coal has been gathered across the entire width of the working face.

What I claim as new is:

1. A gathering mechanism, for coal loading machines having a conveyer and a shoe attached to the forward end of the conveyer, including a gathering member consisting in a tapering auger vertically movable relative to and independently of the conveyer, and means to yieldingly hold said auger into engagement with the ground.

2. A gathering mechanism, for coal loading machines having a conveyer and a shoe attached to the forward end of the conveyer, including a gathering member consisting in a tapering auger vertically movable relative to and independently of the conveyer, means to yieldingly hold said auger into engagement with the ground, and manually operated means for raising the gathering member.

3. The combination with a conveyer, of means to move material onto said conveyer comprising an inverted U-shaped bracket rigidly secured to the conveyer, a shaft journaled in said bracket transversely of the conveyer, means to communicate rotation to said shaft, a shaft extending longitudinally of the conveyer and geared to the first named shaft, an auger carried by the second named shaft, yieldable means to normally maintain the auger in a lowered position carried by said U-shaped member, and means for raising said auger.

4. A gathering mechanism, for loading machines having a conveyer and a shoe attached to the forward end of the conveyer, comprising an auger arranged longitudinally of the conveyer and extending beyond the forward end of the shoe, means to communicate rotation to said auger, a supporting member rigidly secured to the conveyer frame, a forwardly extending spring member attached to said supporting member and normally maintaining said auger in a lowered position, a bracket extending forwardly from said supporting member, and means supported by said bracket for raising said auger.

5. The combination with a conveyer having a shoe at the forward end thereof, of a supporting member carried by said shoe and extending transversely of and above the latter, a shaft extending longitudinally of the conveyer, an upwardly movable hanger for said shaft carried by said supporting member, an auger carried by said shaft and projecting beyond the free end of said shoe, and means to communicate rotation to said shaft and auger.

6. The combination with a conveyer, of a supporting member secured to and extending transversely of the forward end of said conveyer, a shaft supported by said member, 5 means to communicate rotation to said shaft, a second shaft extending longitudinally of the conveyer and geared to the first named shaft, an auger carried by the second named shaft, and a shaft hanger carried by said supporting member and in which the second 10 named shaft is journaled.

In testimony whereof I affix my signature.

JOSEPH F. JOY.
